UNITED STATES PATENT OFFICE

113,553

DESIGN FOR A NOZZLE END FOR A THERMOHYDROMETER OR THE LIKE

Leo Edelmann, Chicago, Ill.

Application December 4, 1937, Serial No. 73,379

Term of patent 14 years

To all whom it may concern:

Be it known that I, Leo Edelmann, a citizen of the United States, residing at Chicago, in the county of Cook and State of Illinois, have invented a new, original, and ornamental Design for a Nozzle End for a Thermohydrometer or the like, of which the following is a specification, reference being had to the accompanying drawing forming part thereof, and in which:

Figure 1 is a view in perspective of a nozzle end

for a thermohydrometer showing my new design.

Fig. 2 is a view in top plan.

Fig. 3 is a view in elevation taken substantially at right angles to the showing in Figure 1.

I claim:

The ornamental design for a nozzle end for a thermohydrometer or the like, as shown.

LEO EDELMANN.
